UNITED STATES PATENT OFFICE.

CHARLES L. LAWRENCE, OF NEW YORK, N. Y.

TOOL KIT.

Application filed January 24, 1925. Serial No. 4,408.

My invention relates to kits for mechanics' tools and particularly for the convenience of automobile mechanics, although, of course, the invention is not limited to 5 their use. In current mechanical practice there are so many sizes of nuts and bolts that a mechanic is obliged to have a complete graded set of wrenches, and usually two sets—one for nuts and the other for cap 10 screws. When these wrenches are carried loosely in a tray or box, an enormous amount of time is lost in trying to find the proper wrench. I, therefore, propose to provide a tray having compartments graded in size 15 located so as to hold wrenches in definite positions and readily accessible. For convenience and safety in storage and transportation I have designed a tray so that it fits in a case in which space is left not only for 20 sets of wrenches but also for various other miscellaneous tools which a mechanic is obliged to carry. This combination tray and case also provides space for carrying overalls and waste as well as miscellaneous small 25 parts such as cotter pins, washers, nuts, bolts, and etc.

The accompanying single sheet of drawings shows one form of construction for carrying out my invention.

Fig. 1 is a longitudinal sectional view of the carrying case showing the tray in a side elevation but partly broken away and with the cover of the case closed.

Fig. 2 is a transverse sectional view of the case showing an end view of the tray and the cover being open.

Fig. 3 is a plan view of the tray removed from the case.

The case 5 preferably has a hinged cover 40 6 and one or more catches or locks 7. The bottom of the case may be provided with small protuberances 8 which serve as casters to facilitate the sliding of the case on the floor or bench. The case is also preferably 45 provided with some suitable form of handle 9. The case may be of any suitable construction, such as aluminum, wood or fibre.

The tray 10 is provided with two spaced-apart longitudinal partitions 11 which are 50 higher in the center than at the ends and provided with some suitable form of handle or handles, such as 12—12. These handles may be formed by cutting out parts of the sides and curling them up as shown. These 55 partitions leave side compartments 13—13 for the reception of miscellaneous articles

and tools. The space between the partitions 11 is divided up into a series of small compartments by means of partitions, such as 14, 15, 16, 17, and 18, and 14', 15', 16', 17', 60 and 18'. These partitions are arranged so as to provide compartments 19 and 20 at the ends and a central compartment 21. These end compartments 19 and 20 may be used for miscellaneous articles and tools. 65 The central compartment 21 may be used for miscellaneous long-handled tools or for waste and the like. The compartments intervening between 20 and 21 are graded in depth so as to conveniently hold the various 70 wrenches of a set beginning at the outer end with the small, short wrenches and with the long wrenches near the center. This arrangement distributes the weight so that the tray is much better balanced than if the 75 long and heavy wrenches were near the outer ends of the tray. The bottom of the tray may be provided with protuberances 22 which will serve as casters to facilitate the sliding of the tray along the floor or 80 bench.

In the cover of the case I prefer to provide one or more compartments in the form of drawers 23 and 23'. These drawers are held in place by plates 24 fixed in the cover 85 of the case. Each drawer may be provided with a handle 25 if desired or with a projecting lip such as 26 by means of which it may be slid back and forth. A space 27 is left between the drawers so that there is 90 room for either drawer to be pulled out or for both drawers to be pulled out part way simultaneously. It will be understood, of course, that the drawers would not be open except when the cover is open, as shown in 95 Fig. 2.

I also prefer to reinforce the case with strips or bands such as 28 at the bottom and 29 at the top, since the kits should be made as light as possible and yet must withstand 100 very severe handling. It will be noted that this form of reinforcing leaves the case smooth on the inside so that the tray may be as large as possible and yet there will be no projection on the inside of the case to interfere with the tray being drawn out of the case. The outer band 29 may also serve as a stop for the cover when the cover is closed, as shown in Fig. 1.

I also prefer to provide slots such as 30 110 in the partition walls 11—11, especially at the ends of the deep compartments so that

in case one of the small wrenches is accidentally dropped into one of the deeper compartments it will be possible to extract it easily by the insertion of some small tool, such as a screw-driver or wire through the slot. Without some such provision it is obvious that it would be necessary to turn the whole tray upside down in order to get a small wrench out of the deep compartment.

10 This would, of course, necessitate disturbing all of the tools or other articles in the tray and would cause great inconvenience as well as annoyance.

It will be seen that when the tray is in position in the case, there is still a substantial amount of room above the center of the tray for any long-handled tools or articles which can be placed in the center compartment. There is also a substantial amount of room in the opposite ends of the case above the tray for such articles as overalls or bunches of waste or cleaning cloths.

I claim:

1. A mechanic's tool kit comprising a case 25 composed of a body and a cover hinged thereto, a tray removably mounted in said body, said tray having longitudinal partitions and transverse partitions, said longitudinal partitions being materially higher 30 in the center than at the ends and the transverse partitions being graded in height so as to provide oppositely disposed compartments of graded depth.

2. A mechanic's tool kit comprising a base 35 having a body and a hinged cover, and a tray removably mounted in said body, said tray having longitudinal partitions and transverse partitions, said longitudinal partitions being materially higher in the center than at the ends and the transverse partitions being graded in height so as to provide oppositely disposed compartments of graded depth, said cover having compartments located in its opposite ends leaving a space between them which is above the center of the tray when the cover is closed.

3. A mechanic's kit comprising a case 50 having a body and a hinged cover, a tray removably mounted in said body and provided with longitudinal partitions disposed on opposite sides of the center, a series of transverse partitions between said longitudinal partitions, said transverse partitions being graded in height from the central portion 55 outwardly toward the opposite ends of said tray to provide a series of compartments of graded depth, and a handle for said tray.

4. A mechanic's kit comprising a case 60 having a body and a hinged cover, a tray removably mounted in said body and provided with longitudinal partitions disposed on opposite sides of the center, and a series of transverse partitions between said longitudinal partitions, said transverse partitions

being graded in height from the central portion outwardly toward the opposite ends of said tray to provide a series of compartments of graded depth, said longitudinal partitions being provided with vertical slots at 70 the edges of some of said compartments to facilitate the removal of wrenches therefrom.

5. A mechanic's tool carrying tray having longitudinal walls, at least one of said walls being higher in its central portion than at 75 its ends and provided with a handle portion in the center, transverse partitions extending between said longitudinal walls to form a series of compartments adapted to receive and hold a graded set of wrenches, and said tray having a shallow lateral compartment extending alongside of said wrench compartments.

6. A mechanic's tool tray having longitudinal partitions higher in the center than 80 at the ends, transverse partitions between the longitudinal partitions to form two sets of compartments adapted to hold graded sets of wrenches, and having a longer waste-receiving compartment in the center and shallower 85 longitudinal compartments for miscellaneous tools on opposite sides of the wrench compartments.

7. A tool carrying tray having longitudinal partitions connected by transverse partitions, said transverse partitions being graded in height from the center outwardly toward the ends of the tray to provide oppositely disposed sets of compartments of graded depths for the purpose of systematically classifying graded sets of wrenches to be carried therein, thus making each wrench of the said graded sets, readily and easily accessible at all times, at least one of said longitudinal partitions having vertical slots 95 at the edges of the deeper compartments 100 to permit the insertion of an instrument for extracting wrenches therefrom.

8. A tool carrying tray having longitudinal partitions connected by transverse partitions, said transverse partitions being graded in height from the center outwardly toward the ends of the tray to provide oppositely disposed sets of compartments of graded depths for the purpose of systematically classifying graded sets of tools to be carried therein, thus making each tool of the said graded sets readily and easily accessible at all times.

9. A tool carrying tray having longitudinal partitions connected by transverse partitions, said transverse partitions being graded in height from the center outwardly toward the ends of the tray to provide oppositely disposed sets of compartments of graded depths for the purpose of systematically classifying graded sets of tools to be carried therein, thus making each tool of the said graded sets readily and easily accessible at all times, and a handle at the 120 125 130

central portion of said longitudinal partitions.

10. A tool box having a base portion divided into compartments, the central of said compartments being further divided into sub-compartments by transverse partitions positioned vertically at various heights graded from the center outwardly ¹⁵ toward the outer walls of the tray to provide compartments of graded depths for tools of different lengths.

10 11. A tool box having a base portion

divided into compartments, the central of said compartments being further divided into sub-compartments by transverse partitions positioned vertically at various heights graded from the center outwardly ¹⁵ toward the outer walls of the tray to provide compartments of graded depths for tools of different lengths.

CHARLES L. LAWRENCE.
